UNITED STATES PATENT OFFICE.

EMMONS M. PARKHURST, OF PHILADELPHIA, PENNSYLVANIA.

SHOE-BURNISHING MACHINE.

SPECIFICATION forming part of Letters Patent No. 448,330, dated December 23, 1890.

Application filed December 21, 1888. Serial No. 294,297. (No model.)

To all whom it may concern:

Be it known that I, EMMONS M. PARKHURST, a citizen of the United States, residing in the city and county of Philadelphia, State of Pennsylvania, have invented a new and useful Improvement in Shoe-Burnishing Machines, of which the following is a specification, reference being had to the drawings which form a part thereof.

10 The object of my invention is to provide a machine which shall hold a shoe and present the heel thereof to a reciprocating burnisher in a manner suitable to cause every part of the heel to be burnished and perform its movements in an automatic manner.

15 My object is also to provide in such a machine means for properly adjusting the various movements.

In carrying out my invention I provide a suitable reciprocating burnisher, preferably having an elastically-supported burnishing surface or part, and in connection with such a burnisher I provide a shoe support or holder adapted to hold the shoe firmly and present 25 the heel thereof to the burnisher and move it relatively with respect to said burnisher that it may have a rocking vertical and lateral reciprocating motion.

In the drawings, Figure 1 is a front elevation of my improved burnishing-machine. Fig. 2 is a detail view showing how the shoe is held and presented to the burnisher. Fig. 3 is a side elevation of the machine, looking toward the right side. Fig. 4 is a plan view 35 of the machine for imparting to the shoe-supporting devices a reciprocating motion. Fig. 5 is a side elevation of my machine, looking toward the left side. Fig. 6 is a sectional elevation of the mechanism for lifting the shoe-supporting devices up to the burnisher. Fig. 7 is a plan view of the machine. Fig. 8 is an elevation of the heel-supporter. Fig. 9 is a vertical section of the same. Fig. 10 is an end elevation of the burnisher. Fig. 11 is a side 45 elevation of the same. Fig. 12 is a detail plan view showing double cranks for the burnisher, and Fig. 13 is a detail view of the adjusting device for relatively adjusting the reciprocating shoe-support with respect to the 50 burnisher.

1 is the frame of the machine, having a col-

umn 2, upon which the burnisher proper and its operating mechanism is supported.

3 is a sliding table, having vertical parts 49, in which the shoe-supporting frames 4 and 5 are guided with provision for vertical movement. These frames 4 and 5 are connected by cross-frames 47. The heel of the shoe is placed on the heel-supporter 7, which is shown in Figs. 8 and 9. The central part of said 60 supporter consists of a rubber center 8, projecting beyond the surrounding leather ring 9, so that no part of the heel can be obstructed during the burnishing operation, and also evenly distribute the pressure put upon the 65 heel while being held by the supporting device. The lip 10 of the supporter 7 catches the front part of the heel and keeps it from slipping during the rocking motion of the shoe. The heel-supporter 7 is attached to a 70 shaft journaled in two bearings 12 and 13 and secured at the end by a nut 14.

The shoe 6 is further secured in its place by a shaft 16, having a claw 17 on the end, which engages with the inside of the sole of the shoe 75 and presses the heel against its supporter. The pressure is applied by a lever 18, turning on a pin 19 and sliding on a circular guide 20, which is provided with teeth for locking the lever at any point desired, according to 80 the height of the heel being burnished. On the pin 19 a small pinion 21 is keyed, the teeth of which are engaged in grooves or teeth 22 on a thicker part 23, carrying the shaft 16, for the purpose of making the shaft move or 85 reciprocate as the lever turns.

On the horizontal shafts 11 and 16 are keyed the beveled gears 15 and 24, which engage gear-wheels 25 and 26, respectively, on shafts 27 and 28. At the other ends of said shafts 90 other gears 29 and 30 are respectively secured. A horizontal shaft 31 gives the shafts 27 and 28, by the gears 29 and 30, their motion. This shaft 31 is keyed to a spur-gear 32, which is rotated by a gear-segment 33, pivoted at the 95 lower end 34 by a fulcrum or pivot pin 35 to a bracket 36, which is secured to the main frame. In the middle of said gear-segment is a slot 37, to which the connecting-rod 38 is secured. This rod is put in motion by the 100 slide 40, to which it is connected at 39. Between pins 41 in the slide is placed a heart-

shaped cam 43, which gives the slide a uniform forward and backward motion or reciprocation. This cam 43 is secured to and driven by a shaft 42. The shaft 42 is driven by a large spur-gear 57, which obtains its motion from a pinion 56, secured on shaft 55. Shaft 55 is driven by a belt 45 from the driving-shaft 44. The speed is reduced in both transmissions, so as to make the rocking motion to the heel slow.

When the shoe has been put in place, as shown in Fig. 2, and fastened by the lever 18, the long vertical lever 45 is pressed down in a horizontal position, as shown in dotted lines 15 in Fig. 1. On this lever is secured a projection or piece 46, Figs. 1 and 6, which rises up when the lever 45 is moved, so that its end will come even with the dotted lines 48, shown in Fig. 1, and thus raises the frame 47 and 20 its connections. The vertical pieces 4 and 5, which are connected by the cross-piece or frame 47, slide in the upright frames 49 of the table 3, and consequently by pushing up the frame 47 the parts 4 and 5 rise and the 25 heel is lifted up against the burnisher.

Beveled gears 25 and 26 are provided with feathers and the shafts 27 and 28 with grooves, so that the gear-wheels will travel with the frames, and yet in operation are in connection 30 with their shafts.

When the lever 45 is pressed down in its horizontal position, the link 51 turns the crank 52, fastened to shaft 53. The turning of said shaft 53 causes the clutch 54 on the shaft 55 to operate and start the machine to give motion to the shoe.

In Fig. 6 is shown attached to the shaft 31 a cam 99, which gives the frame 47 and the shoe which it supports short vertical motions 40 or reciprocations. Besides the rocking motion and this short vertical motion the shoe has also a horizontal motion of a length determined by the height of the heel, so that the burnisher can operate on the entire heel. This 45 is obtained in the following manner: Shaft 55 is provided with a worm 58, which drives a large worm-wheel 59, giving the vertical shaft 60 a very slow motion. To the upper end of the shaft 60 is secured a heart-shaped 50 cam 100, Fig. 4, which makes the pin 61 slide forward and backward horizontally in its bearing 62. To the end 63 of this pin is fastened a lever-link 64, with a slot 65 in the middle and traveling on a guide-stud 66. This 55 stud 66 is adjustable in the guide 69, and is screwed therein by a nut 70. It is also connected to a lever 67, turning on a center 68. By pushing the lever 67 one way or other horizontally the end of the lever-link 64 beyond the stud 66 will be made longer or shorter 60 and its movements and that of the table 3 will correspondingly increase or decrease, and as the stud is stationary it acts as a guide for the link 64. The link 71 is connected at one 65 end to the lever-link 64 and at the other end with the sliding table 3, and will accordingly move the table forward or backward, giving

the shoe its required lateral reciprocating motion. The means for adjusting the shoe with reference to burnisher is shown in Fig. 13, in 70 which 72 is a hand-wheel having a screw 73 passing through a bracket 74, secured to the table 3 or its connections, and this screw is connected to the link 71 by the guide portion 75. By turning the hand-wheel the table may 75 be adjusted without changing the extent of its reciprocations.

The burnisher 50, as shown in Figs. 10 and 11, consists of a piece of steel 76, nicely curved at the bottom and provided above with the 80 slot or jaw 77, in which the upper piece 78 is placed. A pin 79 connects them, and a spring 80 makes the pressure of the piece 76 elastic. A slot 81 is made in the upper piece 78, which receives a feather in the guide 82 to prevent 85 the burnisher from turning. Nuts at the top of the burnisher determine its length, and a spring 84 gives it provision for a vertical vibration. 85 is a gas-jet pipe whose end 86 is close to the burnisher, Fig. 3, to provide a 90 flame to keep the burnisher warm.

The horizontal motion of the burnisher is obtained by a belt 87, transmitting the power from the driving-shaft 44 and increasing the speed to shaft 88. This shaft 88 has two 95 cranks 89, to one of which is attached the connecting-rod 90, and to the other of which is connected the counter-balance 91 of any suitable construction. The rod 90 has a horizontal arm or cross-head 102, to the end of 100 which are fastened rods 92, guided in guides 93. To the ends of the rods 92 is secured the horizontal cross piece or head 95, to which the burnisher is secured. It will now be seen that as the burnisher 50 reciprocates rapidly 105 the heel of the shoe is first thrust up against it by operating the lever 45, and then as the heel rotates back and forth the cam 99 raises and lowers the heel-supporter to insure the retention of the heel in contact with the burnisher simultaneously with this last operation. The cam 43 through its connections causes a given rotary motion to the heel under the burnisher, and the cam 100 induces 110 through its connections a lateral or horizontal reciprocation of the heel-support and all 115 connections.

The burnisher is elastically supported and well adapted to "give" in the proper directions to suit the work being done, and the 120 other devices are designed to impart the requisite movements to suit the shape of the heel.

It is evident that the minor details may be greatly modified without departing from my 125 invention. Hence I do not limit myself to the details shown.

Having now described my invention, what I desire to secure by Letters Patent is—

1. In a burnishing-machine, the combination of the longitudinally-reciprocating burnisher and laterally-movable heel-support and means for reciprocating said heel-support approximately at right angles to the 130

movement of the burnisher, all substantially as shown and described.

2. In a burnishing-machine, the combination of the longitudinally-reciprocating burnisher and oscillating and laterally-reciprocating heel-support and means for oscillating the heel-support and for moving it approximately at right angles to the movement of the burnisher, all substantially as shown and described.

3. In a burnishing-machine, the combination of the reciprocating burnisher and vertically-movable and oscillatory heel-support and means for automatically raising and lowering the heel-support, all substantially as shown and described.

4. In a burnishing-machine, the combination of a reciprocating burnisher, an oscillatory vertically-movable and laterally-reciprocating heel-support, and mechanisms, substantially such as shown and described, for imparting the desired motions to the heel-support.

5. In a burnishing-machine, the combination of a reciprocating burnisher, an oscillatory heel-support, means for imparting motion thereto, and an adjusting mechanism, substantially such as shown and described, to adjust the relative position of the heel-support with respect to the burnisher without varying the extent of the movement.

6. In a burnishing-machine, the combination of a reciprocating burnisher, a heel-supporting device, means to rotate said heel-supporting device, power mechanism to laterally reciprocate said heel-supporting device with respect to said reciprocating burnisher, and hand-lever and intermediate mechanism for raising and lowering the heel-supporting device to or from the burnisher.

7. In a burnishing-machine, the combination of a reciprocating burnisher, a heel-supporting device, power mechanism to laterally reciprocate said heel-supporting device under said reciprocating burnisher, and adjusting mechanism, substantially as shown, to vary the extent of the lateral reciprocations of the heel-supporting device.

8. In a burnishing-machine, the combination of the burnisher 50, having parts 78 and 76 hinged together, and having a spring-connection with a holder or guide, a reciprocating frame, a cam or crank to reciprocate it, and a shoe-supporting device.

55 9. In a burnishing-machine, the combination of the burnisher 50, having parts 78 and 76 hinged together, and having a spring-connection with a holder or guide consisting of frame 82, spring 84, nut 83, a reciprocating

frame, a cam or crank to reciprocate it, and a shoe-supporting device.

10. The combination of a reciprocating burnisher, a movable frame for carrying the shoe-supporting device, two rotary shafts between which the shoe is held, two vertical 65 shafts carried by the frame, a single lower transverse shaft also carried by the frame, bevel-gears between said shafts, substantially as shown, and power mechanism for oscillating the last-mentioned shaft.

11. In a burnishing-machine, the combination of a reciprocating burnisher, a lateral reciprocating table having a supporting device for the shoe, a rotating cam, an oscillating lever operated by the cam, and a link 75 connecting the lever and table, whereby the table is reciprocated by the rotations of the cams.

12. In a burnishing-machine, the combination of a reciprocating burnisher, a lateral reciprocating table having a supporting device for the shoe, a rotating cam, an oscillating lever operated by the cam, and a link connecting the lever and table, whereby the table is reciprocated by rotations of the cam, 85 and means to adjust the fulcrum of the lever to vary its throw.

13. In a burnishing-machine, the combination of a reciprocating burnisher, a lateral reciprocating table having a supporting device for the shoe, a rotating cam, an oscillating lever operated by the cam, and a link connecting the lever and table, whereby the table is reciprocated by the rotations of the cam, and a hand-wheel and screw adjustment 95 for adjusting the connections between the table and link.

14. The combination of the reciprocating burnisher, a vertically-movable frame, a heel-supporting device carried by said frame, hand-lever 100 45, and its projection 46 for raising and lowering the frame and heel-supporting device to or from the burnisher.

15. The combination of the reciprocating burnisher, a vertically-movable frame, a heel-supporting device carried by said frame, a rotating cam 99, and connections between the cam and vertically-movable frame, whereby the movement of the cam reciprocates the frame and shoe-supporting device to or from 105 the burnisher.

In testimony whereof I have affixed my signature.

EMMONS M. PARKHURST.
